Specification for Design.

Patented Sept. 22, 1914.

Application filed May 24, 1913. Serial No. 769,721. Term of patent 3½ years.

To all whom it may concern:

Be it known that I, WILLIAM J. WHITE, a citizen of the United States of America, residing at Niagara Falls, county of Niagara, and State of New York, have invented a new, original, and ornamental Design for Boxes, of which the following is a specification, reference being had to the accompanying drawings, forming part thereof.

The figure in the accompanying drawings shows my new design.

My invention comprises an ornamental

design for a box, in which is represented one pine tree standing in the open field. In the foreground is represented the grass, and in the background a cloud effect in the sky.

I claim:

The ornamental design for a box, as shown and described.

WILLIAM J. WHITE.
